UNITED STATES PATENT OFFICE.

EDWIN B. CUMMINGS, OF INDIANAPOLIS, INDIANA.

VOTING-MACHINE.

1,216,778.

Specification of Letters Patent. Patented Feb. 20, 1917.

Application filed August 28, 1913. Serial No. 787,117.

To all whom it may concern:

Be it known that I, EDWIN B. CUMMINGS, a citizen of the United States, and a resident of Indianapolis, county of Marion, and 5 State of Indiana, have invented a certain new and useful Voting-Machine; and I do hereby declare that the following is a full, clear, and exact description thereof, reference being had to the accompanying drawings, in which like letters refer to like parts.

The object of this invention is to improve the construction and operation of voting machines of the type shown in Letters Patent granted to me, No. 1,010,596, dated Dec. 15, 1911, and No. 1,001,732, dated Aug. 29, 1911.

The chief feature of this improvement consists in arranging the elements of each group for registering and indicating the vote 20 for each candidate, so that the voter can readily change his vote, by merely voting for another straight ticket or candidate and that will re-call or re-set the mechanism which has been operated for voting for the 25 preceding straight ticket or candidate. In this style of voting machine, the voter first operates a key or the like opposite the name of the straight ticket or candidate, and thus sets the parts actuated by the key so that 30 when the voter leaves the voting booth, means is actuated for causing the parts, which have been previously set, to actuate the counter and thus register and indicate the vote. The mechanism here is arranged 35 so that if after operating a key for a certain party or candidate, and the voter wishes to change his vote for another party or candidate, he need not first re-set the mechanism which he has already actuated, but he can 40 immediately vote for the other party or candidate, and when he operates a key for such other party or candidate, it will re-set the formerly actuated mechanism, as well as set the mechanism so as to register and indicate 45 for the new party or candidate, when the voter leaves the booth or machine. This renders vote changing as easy and simple a process as is possible. This vote changing, however, does not apply to the group voting 50 mechanism, but it does apply to the remainder of the mechanism including the "Yes" and "No" voting keys or the "Referendum".

Another feature of the invention consists in arranging the parts of the group voting 55 mechanism so that all of the group voting

keys which have been operated will remain in their operated positions and show that they have been operated until after the voter has left the machine or booth and the counting mechanism has been actuated and the 60 machine as a whole has been re-set. This enables the voter to see and understand clearly and exactly what candidate he has voted for in the group mechanism. This avoids the confusion of the voter, and he 65 can see at a glance at any time, how many in the group he has voted for, and thus know how many more he is still entitled to vote for.

Another feature of the invention provides 70 means for facilitating the coöperation of two adjacent machines whereby one machine is added to another adjacent to it, in order to enlarge the capacity of the machine, and the two machines will operate as one machine, and a single lever will cause the actuation of all registers and indicators in the two machines with means in position to actuate them, and a single lever will re-set 75 all bars of the two machines.

Another feature of the invention resides in the construction whereby the means for voting for the candidate or candidates of a party may be temporarily rendered inoperative when there is no ticket or candidate 80 for that party to be voted for at the election.

The foregoing and other features of my invention will be fully understood from the accompanying drawings and the following 85 description and claims.

In the drawings Figure 1, is a front elevation of my voting machine arranged for two tickets, showing the straight Democratic ticket "voted," but with the vote 90 changed for the lieutenant governor to the Republican candidate. Fig. 2 is a horizontal section on line 2—2 of Fig. 1, with the machine re-set in the condition for the voter to select and operate the keys. Fig. 3 is a rear elevation of the repeating mechanism 95 for the group voting, the parts being in their normal positions. Fig. 4 is the same, showing the parts in position after one key of the group has been operated. Fig. 5 is the same, showing the parts in re-set position. Fig. 6 is a front elevation of the machine 100 with the front plate or frame and associated parts removed, the same being broken away between its ends as shown. Parts of some 105 of the groups are omitted, in order to pre- 110

sent them in their various conditions and positions, the counter actuating and re-setting levers being shown in section. Fig. 7 is a rear elevation of the machine, with the 5 rear plate removed and showing the parts in altered positions by dotted lines, the same being broken away as indicated. Fig. 8 is the rear elevation of the adjacent lower corners of two voting machines, with the parts 10 arranged so that the two machines will operate as one machine. Fig. 9, is a horizontal section of the same on line 9—9 of Fig. 8. Fig. 10, is a section through the part in which the straight ticket bar is mounted. 15 showing said bar in its normal position, the positions of the keys and the slots being indicated by dotted lines. Fig. 11, is the same as Fig. 10, after the straight ticket has been actuated. Fig. 12 is a part of Fig. 11 with 20 the straight key and one other key returned by vote changing.

In the machine shown in the drawings to illustrate my invention there is a rectangular casing 10 with a bottom, top and two 25 sides, and a removable rear plate 11, and the front of the frame has vertical plates 12 at the sides of the machine, cross plates 13 at the top and bottom of the machine, and intermediate plates 14.

30 In the front plate or frame, there are vertical openings between the plates 12 and 14, for the ballots 15, on the ballot holding plates 16, so that the ballots will be visible.

In Fig. 1 there are shown two ballots, one 35 a Democratic ballot, and the other a Republican ballot, and each ballot has the emblem and name of the party thereon with the words "Straight ticket" at the upper end, and also the names of the following officers:

40 "governor", "lieutenant governor", "two senators" and at the lower end, "Yes" and "No". These ballots may be multiplied and lengthened or modified with any number of candidates or officers named thereon.

45 When the ballots are in place, the names of the candidates for the same office will be in the same horizontal row.

The ballot 15 is held in a ballot holding frame formed of plate 16 and a bordering plate 216 which frame is vertically removable. Into this frame the ballot is vertically inserted and also a transparent sheet 116 outside and covering the ballot. The ballot holding frame is slidable in guides 18 secured to the front plates 12 and 14, and plate 16 has perforations 19 and 20 through which the counter wheels 21 and 22 and 23 may be visible. Immediately behind each ballot holding plate 16, there is another plate 123, 55 mounted in the same guides 18, and with similar perforations. The last plate is stationary preferably while the plate 16 is movable vertically, so that when the perforations in the two plates register the counters will 60 be visible, and when they do not register, the

counters will be invisible, which is desirable during the voting. It is immaterial which of these two plates is movable, but plate 123, bears against the counters, and holds them under spindles 24, and, therefore, it should 70 preferably be stationary. The means for moving plate 16 vertically is not here shown, and may be the same as in my former patents.

In the plates 14 the voting keys are 75 mounted, there being one straight ticket key 25 for each ticket, and a key 26 for each candidate and for the "Yes" and "No".

To the rear of plate 14, and secured to the rear of the guides 18 there is a plate 27, and 80 in the space between the parts 14, 18 and 27, a straight ticket bar 28 is located so as to be vertically slidable. Each key has a rearwardly extending pin 30, eccentrically located, which projects through a notch 31 in 85 the straight ticket bar and a slot 32 in said plate 27, curved concentrically with the axis of the key. The notches 31, for all the keys, but the straight ticket key, are elongated longitudinally of the bar, see Fig. 10, but 90 the straight ticket notch need not be elongated, although it is immaterial. These notches 31 are so arranged that when the straight ticket key is operated, it will move the straight ticket bar and operate all of the 95 other keys in the row, and when any other key in the row has been turned back in vote changing after the straight ticket key has been operated, the straight ticket bar will be returned, and likewise the straight ticket key, 100 so that it will not show that there has been a straight ticket vote, although all of the keys in the row will remain operated, excepting any returned during the vote changing. When a second straight ticket key is operated, however, it returns all the keys which had previously been operated. When the straight ticket bar is in normal position, the notches therein permit the operation of any 105 key, except the straight ticket, without causing the movement of the straight ticket bar. 110

Within the machine there is a main or bed plate 40, always stationary and upon which most of the operating mechanism is mounted. This bed plate is a thin metal plate, and in the machine herein shown, is a single plate extending throughout the height and width of the machine, and is mounted at its edges in grooves in the bars 10 of the main frame. The bottom, top and sides of the frame 10 are separable, so that in assembling the machine the bed plate 40 is slipped into the grooves in the bottom and sides of the frame face before the top bar is secured in place. 115

The counter wheels 21, 22 and 23 are mounted upon studs 24 secured in the bed plate 40, see Fig. 6. The three studs are in a horizontal row, spaced apart so that the group of counter wheels will preferably en- 120 125 130

- gage and operate each other. The particular type of counter wheels need not be described, as what is shown is a very old and common counter. The tens wheel 22 and 5 hundreds wheel 23 are spaced somewhat away from the bed plate 40, the units wheel 21, is similarly spaced therefrom by ratchet wheel 43, which is secured to the counter wheel 21 and lies against the bed plate 40. 10 The units wheel is actuated by a sliding pawl 44, which lies against the bed plate 40, see Fig. 6, and at its left hand end has a pin 45, projecting rearward therefrom, through a horizontal slot 46, in the bed plate and 15 rearward beyond the bed plate by the pawl actuating bar 47. There is a downward arm 48, midway on each pawl 44, with a plurality of teeth adapted to engage a plurality of teeth of the ratchet wheel 43, above its pivot, so that when the pawl 44, is given a straight 20 horizontal movement to the right by the bar 47, behind it, after the bar has been moved to the left and set by the voting key, the pawl will actuate the units wheel one notch, 25 see the upper end of Fig. 6. The object of the plurality of teeth in the arm 48, of the pawl 44, is to cause all those notches to inter-lock with the teeth of the ratchet wheel 43, and hold said ratchet wheel in position. 30 This result follows, although the pawl 44, is 35 slideable, because of the relation to each other of the teeth on the arm 48, which prevents any movement of the ratchet wheel 43, until after the pawl 44 has been moved away. 40 This arrangement prevents a person from inserting a wire through the perforations in plates 16 and 23, and moving the units wheel 21. The units wheel is thereby locked from backward movement by the locking lever 50 fulcrumed between its ends on the pin 51, in the bed plate 40, and in a substantially horizontal position, so that one 45 end will be light and have a hook on it to engage a tooth of the ratchet wheel 43, and the other end will be heavy, so that gravity 50 will move the hooked end of the lever toward the wheel 43. To make the latter lock positive, an arm 52 extends down from the left end of the pawl 44, and has an inclined 55 surface which engages an inclined surface of the heavy end of the locking lever 50, so as to positively force and hold the locking lever against the wheel 43 and prevent its moving backward. 60 The sliding pawl 44, which actuates the counters, is moved into and out of position for actuation of the counter by a lever 53 which is actuated by the pin 30 on a key 25 or 26. The lever 53 is pivoted on a stud 54 65 in bed plate 40, and it has three arms, one arm 531 which is engaged and actuated by pin 30 on the key. The other end of lever 53 has an upper arm 532 projecting from the lever and in position to engage the right-hand end of the sliding pawl 44 when
- the lever is actuated by the operation of the key, and moved to the left from the position shown in the upper group in Fig. 6, to the position shown in next group below. This places the pawl in position for the actuation 70 of the counter when the voter leaves the booth, as will be explained hereafter.
- The chief characteristics of the operation of the registering and indicating mechanism, so far described, are substantially the 75 same as in my former patents. But to enable a voter to change his vote readily, the lever 53 is provided with another arm 533, in position to engage a shoulder 441 on the sliding pawl 44. When the lever 53 is given 80 a return movement from the position shown in the second group to that shown in the first group of Fig. 6, the right hand end of the pawl 44 will be lifted and moved to the right, as shown in the third group in Fig. 85 6, until it is returned to its normal position where it was before the key had been operated, and in making this movement, the pawl 44 does not actuate the counter. This 90 merely undoes what before had been done 95 by the voter, so that he can proceed to vote for some other candidate for the same office, without more than one vote being registered.
- The lever 53 is returned to its normal position, during vote changing, by a double arm 55 pivoted on a stud 56 in the bed plate 40 and having one arm 551 that would engage the arm 531 of the lever 53, and another oppositely projecting arm 552 projecting into position to be engaged by the shoulder 581 on the sectional locking bar 58 immediately to the right of said lever 53. There is a sectional locking bar 58 for each 100 candidate and ticket, all the sectional locking bars in each horizontal row constituting a series co-operating and abutting, so that when any locking bar is moved laterally, it will move the other locking bars in 105 advance of it. Each sectional locking bar 110 58 has a pin 582, which projects through a slot 60 in the bed plate 40, see Fig. 7, which is located just above the slot 46. The pin 582 projects beyond the bed plate 40 so as to be engaged by the re-setting bar 47 which 115 returns the locking bar to its normal position. Also, each sectional locking bar 58 has at its right hand end a pin 583 which projects through a slot 61 in the bed plate 40, being headed on its rear end, so that it 120 guides the locking bar and holds it from escape. Each locking bar 58 has at its right hand end a notch 584 adapted to be engaged by the arm 532 of the lever 53, when the latter is actuated by a voting key, whereby 125 the locking bar is actuated toward the left into locking position. These locking bars 58 are arranged like those in my former 130 patents, but in the former their chief function was to prevent the operation of any

other voting key in the same row, for the same office, but in my present machine, the chief object of the bars 58 is to permit the operation of another voting key for the same office and at the same time to un-vote any other voting key which has been operated for the same office. And they do this work whether operated to the right or to the left. Thus, if the left hand key is operated, the locking bar will actuate the arm 55, which will return the first operated lever 53 and voting key, to their original positions. On the other hand, if the right hand key be first operated, the operation of the right hand key will throw the arm 55 up to the right so that the locking bar will return the right-hand lever 53 and voting key to their original positions. When the second key voted is at the right, the previously operated lever 53 is returned by the arm 55 being actuated by the locking bar. If the second key voted is at the left, the reverse takes place, the previously operated lever 53 being returned by the locking bar, it being actuated by the arm 55.

It is to be noted that when the second voting key for the same office or ticket is operated, the previously operated key was returned to its original position, and it also returns the straight ticket bar and straight ticket key to their original positions. Hence, the various groups of registering and indicating mechanism for the different tickets and candidates in this machine, excepting the group voting mechanism, may be operated at will without any interlocking, and yet will prevent any duplicate voting. The voter may play over the keys of the machine, operating any voting keys he may wish; but when he goes out of the booth, or leaves the machine, only the last voting key for each office or ticket which he has operated will be counted, all the others being automatically returned to their original positions as completely as if they had not been operated by the voter.

When the voter enters the booth or approaches the machine to vote, only the lever 65 at the left hand corner of the machine is operated, and he can re-set the machine readily for voting. Then the voter operates such voting keys as he wishes, and thus places the sliding pawls 44 in position to operate the counters for such voting keys. Then as he leaves the machine or booth, the lever 66 is operated which is located at the lower right hand corner of the machine. And this, as has been explained, moves all of the sliding pawls 44 to the right and actuates the proper counters. Said levers 65 and 66 are fulcrumed or pivoted on pins 67 on the bottom frame bar 10 of the machine and the interior ends of said levers engaging the ends of a horizontally reciprocating bar 70 which is held in place by

guide pins 71 projecting up from the bottom bar 10 and automatically actuates each vertical bar 47 by bell crank lever 73 fulcrumed by the pin 74 to the bed plate 40 and said lever. Said lever 73 has a slot 75 in each end which engages the pins 76 and 77, which are in the bars 70 and 47, respectively. Each vertical bar 47 is pivoted by a plurality of pins to one end of each of the link bars 78 and the other ends of said link bar 78 are pivoted at 79 on the bed plate 40, as shown in Fig. 7. The link bars 78 are inclined so as to be substantially parallel with each other, and with the one arm of the bell crank lever 73, so that when the bar 70 in Fig. 7 is moved to the right by the lever 65, it will move the entire bar 47 laterally throughout its length, and to the left as shown in said figure to the dotted line position. This movement of bar 47 causes it to move the pawls 44 and locking bars 58 to the right, see Fig. 6, and thus actuate the counters and re-set the locking bars.

After the machine has been operated as stated, it is locked against further operation until the lever 66 is actuated so as to move the vertical bars 47 away from the locked position to the position shown in Fig. 7, and permit the sliding pawls 44 and the locking bars 58 to be moved to the left, see Fig. 6, permitting the voting keys again to be operated. It is observed that the bars 47 are independent of each other, although they are operated by the same bar 70.

The foregoing mechanism constitutes a complete voting machine and as heretofore may be comparatively small, suitable for small ballots, and by the combination of a plurality of such machines coöperating to make a larger voting machine suitable for elections having many tickets and candidates, and be sectional so that the machine may be readily adapted for any election. Only one section, for instance, may be used for primary elections, or simple municipal elections, and State tickets may be put in one section, the county tickets put in another section, and if necessary, the national ticket in another section. In some States all of these tickets are voted at one election, while at another election only one or some of the tickets are voted.

This enlargement of the capacity of the voting machine is accomplished by placing the sections of smaller voting machines side by side, and providing means for operatively connecting the series of bars 70. In the form herein shown there is merely a sliding block 80 located between and secured against the ends of the bars 70 of the two adjacent machines slidably mounted in said machines by pins 81 working in the slots. Levers 65 and 66 in the adjacent ends of the two machines are removed. There-

fore, when the lever 65 at the left hand end of the entire group of machines is operated, it will push all of the bars 70 to the right, and when the voter leaves the booth or machine and the lever 66 is operated, it will push all of the bars 70 to the left.

It is desirable for voting machines to have a "yes" or "no" "referendum" voting mechanism and that is here illustrated in the two lower groups of voting keys, seen in Figs. 1 and 6. The chief difference between this part of the voting mechanism and that for the general candidates, is that here there is vertical interlocking, that is, when a key is operated, it will lock its companion key above or below and the vote changing lever is omitted. The upper lever of the lower pairs of levers 53 is modified in form, having a downward extension or arm 535 which projects into the path of the arm 532 of the lever 53 below, so that the operation of either one of said levers will return or reverse the other lever. If a voter votes "Yes", the key will move the upper lever 53 and the downward arm 535 will move to the right, and engage with the arm 532 below. If he votes "No", the key will move the lower lever, and its arm 532 will engage the downward arm of the lever above. This enables the voter to change his vote in this part of the machine as readily as in the other part thereof. The "yes" and "no" mechanism does not differ from the other except in the omission of the lever 55 and the addition of the arm 535 to the upper lever 53, and there are no abutting bars. The bars 158 in the "yes" and "no" mechanism are the same as the locking bars 58 above, excepting that they do not abut, and are therefore not locking bars, but they perform the other functions of the bars 58, interlocking the downward movement of the sliding pawls 44, as the latter are operated by the arms 533 of the levers 53. In other words, there is no connection horizontally between the "yes" and "no" mechanism, and they are not connected within a straight ticket bar, for they are nonpartisan.

The group voting mechanism is included in the voting machine herein shown, and the chief feature is the arrangement thereof so that all the keys operated will remain in an altered position, and the voter can see exactly what keys he has operated, and thus be sure to operate the number he is entitled to operate. In Figs. 1 and 6 the third and fourth group of keys and key operative mechanism from the bottom, are for group voting, and the keys as shown herein are for electing "senators", where the voter is allowed to vote for any two senators in the group of candidates for senators. The voting keys and the parts thereby actuated, including the counters, are the same in the

group voting mechanism, as in the previous similar voting mechanisms herein described, excepting that there is a pivoted lever 153 which differs from the pivoted arm 53 in shape, and contact points with the other parts, and the shoulder 585 on the locking bar 58 is differently positioned from the shoulder 581 and in the repeating mechanism, a spring 87 through levers 85, see Fig. 7, presses the locking bars 58 to the right, as shown in Fig. 6, so that upper arm of the lever 153, when operated, will push the locking bar over to the left to the full limit, and escape from the shoulder 584 thereof. The spring pressure referred to will immediately throw the locking bar back to its normal position, and the lever 58 which has been operated together with the voting key, will remain in the operated position, and show the voter that he has operated it.

There is a shoulder 585 on each group voting locking bar to the left of the shoulder 581. In the machines here shown, the locking bars of the regular and group voting mechanism are made alike, and may be so made on the machine, but in the regular voting mechanism the shoulder 585 does not function while in the group voting mechanism the shoulder 581 does not function.

The chief object of the pivot arm 155 in the group voting mechanism is to prevent the voter from operating two keys simultaneously. Hence, it has a surface against which the extreme end of the arm 531 on the lever 52 abuts and pushes as it is moved upwardly by the operation of the voting key. When the pivoted arm 155 is thus moved upward it has a shoulder on its upper end to engage and lock with the shoulder 585 on the locking bar, and prevent the further operation of such locking bar, until it has again been re-set after the voter leaves the machine. Hence, if a voter should undertake to vote after he has voted all allowed him, this arm 155 will interfere, because the lever 153 will be pushing it in one direction and the locking bar 58 will be pushing it in the other direction, and therefore the parts cannot move. To enable the lever 153 in the group voting mechanism to be returned by the counter actuating movement of the sliding pawl, the pin 583 can move upward in the enlarged end of the slot 61 as the end of the locking bar 58 in which the pin 583 is mounted is pushed upward by the arm 532 on the lever 53 as it is being returned.

The repeating mechanism which limits the number of candidates for which one can vote in the group voting mechanism is illustrated in Figs. 2 to 7. On the rear side of the bed plate 40, a frame 800 is secured. It is built up of a main or rear plate 801 and a plate 802 is secured thereon. In the

plate 801 there is a longitudinal slot 803 in which a notch bar 81 is vertically slidable, by means of the pins 811. The bar 81 has two or more pairs of notches 812 on the two opposite sides thereof, the numbers of pairs of notches agreeing with the number of candidates in the group voting mechanism, for which one is entitled to vote. The slot 803 is longer than the notch bar 81 so that said bar is vertically movable therein, and said vertical movement is limited by a pin 807.

The limiting bar 81 is elevated one notch at a time, as each candidate is voted for, by the pawl 82, which is pivoted by the pin 821 to the frame 83 which is vertically movable in the main frame. At every vertical movement of the frame 83, the pawl 82 engages a notch and elevates the bar 81 and pawl 84, by gravity, drops into the opposite notch and supports the bar 81 in its elevated position. Thus the pawls 82 and 84 elevate the bar 81 step by step and it is stopped by the pin 807 and then the mechanism is locked from further operation and prevents further voting in the group voting mechanism.

The sliding frame 83 is elevated by the arms 85 pivoted at 851 to the frame 800 and one projection 852 which engages a lug 831 on the sliding frame 83 and elevates said frame as the arm 85 is oscillated by the left hand end of the locking bar 58, engaging a projection 853 from the pivot arm 85. In other words, this arm 85 merely converts the horizontal movement of the locking bar 58 into vertical movement of the frame 83. There is one pivoted arm 85 for each locking bar 58.

The frame 83 is returned or drawn downward by the spring 87, one end of which is secured to a pin 931 on the movable frame 83 and the other end to the pin 808, the stationary frame 802 forming a part of the plate 800. A lever 88 is fulcrumed at 881 between its ends on a pin in the plate 802 and is operated by a loop 471 on the vertical bar 47 on the re-setting mechanism, engaging the end 883, and when that end is elevated the other end of the lever, by reason of a center concave surface 884, engages a lug 822 on pawl 82. This disengages the pawl 82 from the notch bar 81, and at the same time by a convex surface 885 engages a pin 842 on the pawl 84, and disengages it from the bar 81. This is for the purpose of re-setting the repeating mechanism. By changing the number of pairs of notches in the bar 81, and correspondingly changing the limit of its movement the repeating mechanism may be adopted to control the group voting mechanism for any desired number of candidates. Only the number of candidates equal to the limited number of pairs of notches can be voted for.

If it be desired to include the group ticket in the straight ticket, that may be done through the following means:

As seen in Figs. 6 and 7 a bar 280 is mounted on the main plate 40 so as to be vertically slidable and it is set off immediately to the left of the locking bars and extends up almost to the straight ticket locking bar. Said bar has in it a vertical slot 281 through which a pin 282, from the plate 40, projects. This pin guides and limits the movement of said bar. The said bar 280 lies in front of the plate 40 at a position in front of the repeating mechanism, as shown in Fig. 7, and a pin 480 is secured in the bar 280 and projects through a vertical slot 481 in the plate 40, as shown by dotted lines in Figs. 6 and 7, and projects and is secured to the repeater so that when the bar 280 is lowered or elevated they change the position of the repeater. In one position, when, as shown in Fig. 7, said repeater stops the locking bars 58 of the group voting section of the machine, the pin 182 on said locking bars engages the point 180 of the arm 85 heretofore explained. When, however, the repeater is lowered so that the pin 182 on the locking bar registers with the recess 181 in the arm 85 then the repeater is inoperative so far as the group voting section is concerned and the straight ticket bar will operate the group voting keys just as it will operate any of the other keys.

The repeating mechanism is held in its upper and normal position, as shown in Fig. 3, by the bar 280 and the arm 382 on the bar 380, as shown in Fig. 6. The arm 382 engages a corresponding notch 283 in the lateral edge of the bar 280, when said bar is elevated as shown in Fig. 6. The rocking bar 380 is fulcrumed to the plate 40 at 381 and the upper end of said bar rests against the left hand locking bar 58 of the straight ticket key. Therefore, when the straight ticket key is operated said left hand locking bar will be moved to the left, somewhat, thus disengaging the arm 380 from the notch 283 and permit the said bar and the repeater to drop as far as the slot 281 and pin 282 will permit. In such lower position the recesses 181 in the arms 85 will register with the pins 182 in the group voting locking bars so that the repeater will not interfere with the operation of said group voting key with the straight ticket bar. After thus voting a straight ticket and the voter is leaving the booth and operates the vertical bar 47, as heretofore explained, from the full line position to the dotted line position in Fig. 7, then the arm 147 on the said bar 47 will engage the lower end of the repeater and lift it and the bar 180 until the arm 382, see Fig. 6, enters the notch 283 in the bar 280 and thus holds the repeater in elevated and normal position. When there is no

candidate or ticket of a party, the same may be rendered inoperative by removing the pin 76 or pin 77, see Fig. 7, which connects the lever 73 with the horizontal operating bar 70.

I claim as my invention:

1. A voting machine including a register, a sliding pawl normally out of position to actuate the register and having a projection 10 near one end, a voting key operated lever with two arms, one arm so arranged that when the lever is moved in one direction it will set the sliding pawl in position to actuate the register, and the other arm engaging the projection of said pawl, so that a return movement of the lever will lift and return the pawl to normal position without actuating the register.

2. A voting machine including a register, 20 sliding pawl for actuating the same which is normally out of actuating position, and which has a projection near one end, means for giving the pawl its register actuating movement after the pawl has been set in register actuating position, and the voting key operated by the lever provided with two arms, one arm arranged to move the pawl when the lever is operated to a register actuating position, and the other arm engaging 25 said projection of the pawl, so that a return movement of said lever, before the register has been actuated will return the pawl to its normal position without actuating the register.

3. A voting machine including a plurality 35 of registers, a sliding pawl for actuating each register, each sliding pawl being normally out of register actuating position, a voting key operated lever having a plurality of arms, one arm adapted to move said pawl when said lever is operated into a register actuating position, and the other arm when the lever is returned adapted to return said pawl to its normal position without actuating 40 its register, and means operated by one of said operating levers for returning a previously operated lever, and thus returning the pawl of the latter to normal position without actuating its register.

4. A voting machine including a plurality 50 of registers, a sliding pawl for each register normally out of register actuating position, a voting key operated lever with two arms, one arm adapted when the lever is operated to move its pawl into register actuating position, and the other arm when the lever is returned, adapted to return the pawl to normal position without operating the lever, a sliding bar moved by each lever when 55 operated, and a pivoted arm actuated by said sliding pawl for returning a previously operated lever.

5. A voting machine including a series of 60 registers, a sliding pawl for each register which is normally out of registering posi-

tion, a voting key operated lever with two arms, one arm adapted, when operated to move each pawl to a register actuating position, and when returned, to return said pawl to its normal position without 70 actuating the register, and a sliding bar actuated by each lever when it is operated, the series of sliding bars abutting against each other, and a pivoted arm in position to be actuated by said sliding pawl, whereby 75 the lever, last operated in the series will be returned, and any previously operated pawl in the series will be returned to its normal position without actuating its register.

6. A voting machine including a series of 80 registers, a sliding pawl for each register which is normally out of registering position, a voting key operated lever with two arms, one arm adapted, when operated, to move each pawl to a register actuating position, and when returned, to return said pawl to its normal position without actuating the register, and a sliding bar actuated by each lever when it is operated, the series of 85 sliding bars abutting against each other, and a pivoted arm in position to be actuated by said sliding pawl, whereby the lever last operated will be returned, and any previously operated pawl in the series will be 90 returned to its normal position without actuating its register, and means for giving the last operated sliding pawl in the series its register actuating movement.

7. A voting machine including a plurality 95 of registers, a sliding pawl for actuating each register and arranged normally in position not to actuate its register, and a lever for each pawl arranged when moved forward to set the pawl in position to actuate its register, and when given the return movement it will return said pawl to its normal position, said levers being arranged with reference to each other, so that the forward operation of one, will cause the return movement of the other.

8. A voting machine including a plurality 100 of registers, a sliding pawl for actuating each register and arranged normally in position not to actuate its register, a lever for each pawl arranged when moved forward to set the pawl in position to actuate its register and when given the return movement it will return said pawl to its normal position, said levers being arranged with reference to 105 each other so that the forward operation of one will cause the return movement of the other, and means for giving actuating movement to the pawl which is set in position to actuate its register.

9. A voting machine including a plurality 115 of registers, a sliding pawl for each register normally in position not to actuate the register, a lever for each pawl having a pair of arms, one arm arranged when the lever is given forward movement, to set the pawl 120

125

130

in a register actuating position, and another arm, when the lever is returned, for returning the pawl to its normal position without actuating the register, a pivoted arm, one of 5 said levers having a third arm projecting into engagement with said pivoted arm, a sliding bar between said levers and in position to be returned by said pivoted arm so that the forward movement of one lever, 10 will cause the return movement of the other lever, and means for actuating the pawl which is set in register actuating position.

10. A voting machine including group voting keys and locking bars, a repeater 15 adapted when in one position to control and limit the operation of the said group voting keys and locking bars, a straight ticket voting mechanism adapted to operate the group voting keys and locking bars when not controlled by the repeater, and means operated 20 by the straight ticket voting mechanism for causing the movement of the repeater to a noncontrolling position, whereby the group voting keys will be operated by the straight ticket mechanism.

11. A voting machine including group voting keys and locking bars, a repeater which in one position controls and limits the 30 operation of said group voting keys and locking bars, a straight ticket voting mechanism, registering mechanism, means movable by said voting keys in a position to actuate said registers, means operable by the voter as he uses the machine for causing the 35 actuation of the registers, and means operated by the straight ticket voting mechanism for causing the repeater to be moved to a non-controlling position and means moved by the said means for causing the actuation 40 of the registers for returning the repeater to the voting position.

12. A voting machine including group voting keys and locking bars, a vertically 45 slideable repeater which in one position engages said locking bars and controls the operation of said group voting keys and locking bars, a vertically movable bar connected with said repeater mechanism and having a notch in it, a rocking bar provided with 50 an arm for engaging said notch in said vertical movable bar and holding it and the repeater in an elevated position so as to control and limit the group voting keys and locking bars, a straight ticket voting mechanism 55 including a locking bar adapted when actuated to release said rocking bar and per-

mit the repeater to drop into a position where it will not interfere with the operation of the group voting keys and locking bars, registering mechanism, and a bar movable by the voter as he leaves the machine for causing the actuation of said registering mechanism, which bar has an arm adapted to elevate said repeater and the bar connected with it so that said repeater and bar will 60 be caught by the arm on the rocking bar and the repeater held in position for limiting and controlling the operation of the group voting keys and locking bars.

13. A voting machine including register, 70 mechanism for each candidate of a party, means adapted to be placed in position by the voter for actuating said registering mechanism, a vertically disposed bar for operating all of said register actuating 75 means, a horizontal reciprocable bar adjacent the ends of all of said vertically disposed operating bars and adapted to be operated by the voter as he leaves the machine, and a removable connection between 80 said horizontal bar and each of said vertically disposed bars whereby any of said vertically disposed bars may be temporarily rendered inoperative when not required.

14. A voting machine including a plurality of voting keys in the same horizontal row and each key provided with an extension adapted to be moved when operated from a downward position to substantially a horizontal position, a locking bar for each 90 key, all excepting the advance locking bar having a shoulder in the forward end thereof, and a pivoted dog adapted to engage the shoulder of the locking bar and to engage the extension of a voting key which has been 95 operated and be locked thereby and thus prevent the operation of the locking bar.

15. A voting machine including a plurality of voting keys arranged in a vertical bar and the key above the lower key having a 100 downward extension in position to engage and be engaged by the key below the same when actuated so that when either key is actuated, it will return the other key to an inoperative position.

In witness whereof, I have hereunto affixed my signature in the presence of the witnesses herein named.

EDWIN B. CUMMINGS.
